UNITED STATES PATENT OFFICE.

ALBERT W. ENGEL, OF CHICAGO, ILLINOIS.

PICTURE-MOUNTING DEVICE.

1,386,771.

Specification of Letters Patent. Patented Aug. 9, 1921.

Application filed May 14, 1920. Serial No. 381,248.

To all whom it may concern:

Be it known that I, ALBERT W. ENGEL, a citizen of the United States, residing at Chicago, in the county of Cook and the 5 State of Illinois, have invented certain new and useful Improvements in Picture-Mounting Devices, of which the following is a specification, reference being had to the accompanying drawings, forming a part 10 thereof.

The purpose of this invention is to provide an improved device for securing photographs or other pictures and cards upon a mat, card, or other mount, in a convenient 15 and ornamental manner. It consists in the features of construction shown and described, as set out in the claims.

In the drawings:

Figure 1 is a plan view showing a card or 20 picture secured to a mount by the corner fitting embodying this invention.

Fig. 2 is an enlarged view of the device located at the corner of the picture.

Fig. 3 is a detail view of the device unattached.

Fig. 4 is a view similar to Fig. 2, showing the device arranged in a different manner.

Fig. 5 is a view similar to Fig. 4, showing 30 a slightly modified form of the device.

Fig. 6 is a detail view of the device shown in Fig. 5.

Fig. 7 is a view showing the device illustrated in Fig. 5, but used in a different way.

The drawings represent a mount, 1. 2 is a picture to be mounted. 3 is a corner piece or mounting device. In the form shown in Figs. 1 to 4 inclusive, said corner piece or mounting device is a substantially right- 35 angular or L-shaped piece of card or paper 40 of suitable thickness having gum or mucilage applied to one side. There is an angular aperture, 4, formed by cutting or slitting the mounting device, no material being cut 45 away. In Fig. 3 in dotted line, is indicated the possibility of producing the device without waste of material, the extending portions and widths thereof being equal.

The form shown in Fig. 6 may be similarly produced, but with the exception that 60

a corner, 6, shown in dotted line, is removed, leaving the slits, 4^x, open.

In both the forms shown there are two slits at an angle to each other, which in one of the forms meet forming an angular or 55 L-shaped slit. The purpose of slitting in all of the forms is to admit a corner of the card or picture which is to be mounted, so that a substantial part of it shall be on each side of the mounting device without obscuring the outline of the corner of the card, (though said device may be formed and applied in such manner as illustrated in Fig. 7, so as to exactly overlie the corner in conformation therewith), and for this purpose,—for admitting the corner of the card as stated,—obviously the two slits or portions of the angular slit must be in free communication with each other at their proximate ends. This is effected by their meeting 60 in the form having the L-shaped slit, and by their emergence at the edge of the same side of the device in the other form. 65

The device may be applied in various ways, producing different artistic effects; 70 the first shown producing the appearance of an open square with one corner thereof omitted; in Fig. 4 the same device is made to appear as having the peculiar formation of a ziz-zag strip placed at the corner. 75 These results are produced by introducing the corner of a picture in the slit, 4, so that it will overlap or underlie the right-angle corner, 7, included in the angle formed by the angular slit, 4. By comparing Figs. 4 80 and 5, it will be noticed that the same resulting effect is produced by both forms; the device used in Fig. 5 being the one detailed in Fig. 6, and the absence of a corner piece thereof not making any change because of the way it is applied. But, in Fig. 7, the last mentioned form is shown applied with the right-angled portion, 7^x, resulting 85 from the angle slit and the corner of the picture concurrent with portions or tabs, 8, 90 8, beyond or outside thereof gummed to the mount, 1.

I claim:

1. A picture mounting device consisting 100 of a corner fitting gummed upon one side,

adapted to be secured partly to the picture angular slit in said fitting adapted to re- 10
and partly to the mount therefor, and for receive the corner of a picture for lapping
that purpose having two slits at an angle the corner portion over a part of the fitting
to each other with open communication at and under the remainder.

5 their proximate ends

In testimony whereof, I have hereunto set
my hand at Chicago, Illinois, this 12th day 15
of a corner fitting gummed on one side, of May, 1920.

2. A picture mounting device consisting
adapted to be secured partly to the picture
and partly to the mount therefor; with an

ALBERT W. ENGEL.
